UNITED STATES PATENT OFFICE.

JAMES REAGAN AND WILLIAM REAGAN, OF PHILADELPHIA, PENNSYLVANIA; SAID WILLIAM REAGAN ASSIGNOR TO SAID JAMES REAGAN.

GRATE.

No. 925,787.

Specification of Letters Patent.

Patented June 22, 1909.

Application filed September 4, 1908. Serial No. 451,641.

To all whom it may concern:

Be it known that we, JAMES REAGAN and WILLIAM REAGAN, citizens of the United States, residing in the city and county of 5 Philadelphia, State of Pennsylvania, have invented a new and useful Grate, of which the following is a specification.

Our invention relates to a new and useful shaking grate and consists in providing a 10 reversible lifting fire bar which can be used with or without choppers.

It further consists of novel means for mounting the same whereby a lifting fire bar can be removed independently of the 15 others.

It further consists of other novel details of construction, all as will be hereinafter fully set forth.

Figure 1 represents a side elevation of a 20 reversible lifting fire bar showing the rocking bars upon which the same is mounted. Fig. 2 represents a side elevation showing a reversible lifting fire bar with the parts disconnected. Fig. 3 represents an end elevation thereof showing a chopper on opposite sides thereof, in dotted lines. Fig. 4 represents a top plan view of a reversible lifting fire bar. Figs. 5 and 6 represent said elevations, on a smaller scale, showing the 30 bar in its different positions.

Similar numerals of reference indicate corresponding parts in the figures.

Referring to the drawings:—We have found in shaking grates that it is of advantage to provide a construction where there 35 are no dead points in the fire and in which free passage of air is permitted and caused in order that a suitable draft is provided and we have further found that in some instances it is of advantage to be able to raise a fire bar in either one direction or the other.

Our invention is designed to accomplish these results and in the drawings we have 45 shown a construction for carrying out the same, but it will be evident that various changes may be made which will come within the scope of our invention and we do not therefore desire to be limited in every instance to the exact construction as herein shown and described but desire to make such changes as may be necessary.

We desire it understood that our reversible fire bar is adapted for use on any suitable 55 construction of grates and we desire to use

the same either in conjunction with rocking choppers or not, as may be necessary.

In some instances we may alternate the reversible lifting fire bars with choppers or we may make sections entirely of the 60 reversible lifting fire bars, the use and arrangement of the parts, depending upon the conditions.

1 designates a hollow reversible lifting fire bar which is preferably formed of the upper 65 and lower sections 2 and 3 respectively, the upper section in the present instance being provided with the top face 4 having the slots or perforations 5 therein and having on the face thereof at the opposite ends 70 thereof, the laterally extending shoulders 6 and 7. The section 2 is provided with the downwardly extending sides or wings 8, which are provided with the slots or perforations 9 and the edges 10 and 11 of said 75 sides 8, converging toward each other. The section 3 of the lifting fire bar is formed with the front and rear faces 12 and 13 which are provided with the slots of perforations 14 and the inner edges 15 and 16 80 of the section 3 converging toward each other from the top downwardly. Any suitable means for connecting the section may be employed and in the drawings we have shown the openings 17 in the upper section 85 adapted to receive the tongue 18 of the lower section.

19 designates ears or lugs projecting from the lower section, which is adapted to be pivotally connected with a bar 20, which is 90 connected with suitable actuating mechanism for operating the reversible lifting fire bar.

21 designates rocking bars upon which we preferably mount the choppers 22 on opposite sides of the reversible lifting fire bar 1 95 and upon the said rocking bar 21 we mount the sleeves 23 which have, projecting from the opposite ends thereof, the lugs 24, which are adapted when in normal position, to engage the sides of the reversible lifting fire bar 1 to prevent lateral movement thereof. Each of the reversible lifting fire bars 1 is adapted to be supported upon two of the rocking bars 21, which carry the sleeves 23 which are movable in the slots 25 formed 100 between the converging edges of the upper and lower sections and upon opposite sides of the depending wings 8, said slots 25 being preferably curved whereby it will be understood that the supports for the bars serve a 105 110

double purpose, that is one of the supports for each bar acts as a guide for the bar in its movement, while the other support acts as a pivot for the bar, depending upon the direction of movement of the bar. It will be noted that while we have described the slots 25 as if they were two slots, we desire it understood that in some instances, and as shown, these may be considered as one slot, 10 oppositely converging, and that while we have in our claims called for a slot, if the slot is made in two parts, the function and operation will be the same, and hence will come within the scope of our claims. In the upper section we preferably form the two seats 26 and 27 on opposite sides of the depending sides or wings 8, said seats being preferably curved to seat the sleeves 23 and thus form a proper bearing between the parts, so that the rocking of the bar in either direction will be properly accomplished either of the seats forming the support or pivot upon which the lifting fire bar is rocked depending upon the direction of movement thereof. By proper operation of the bar 20, for example, in the direction indicated by the arrow in Fig. 1, one end of the reversible lifting bar is elevated into the position seen in Fig. 5, the slot 25 upon one side permitting this movement and the rocking bar 21 on the other side serving as the pivotal support therefor, but when the bar 20 is moved in the opposite direction, the other end of the reversible lifting fire bar 35 is elevated into the position seen in Fig. 6 and the other rocking bar 21 will serve as the support for the opposite end of the lifting fire bar. By this means it will be noted that the lifting fire bar can be rocked in either direction as desired with evident results. We desire it understood that the reversible lifting fire bars can be used in conjunction with the rock choppers or not as previously stated, if so desired.

45 In order to remove any one of the lifting fire bars from a grate without disturbing the others, the upper section 2 is disconnected from the lower and can be removed and the latter is released from engagement with the bar 20 after which the lower part can be removed.

It will be understood that the lugs 24 on the sleeves 23 engaging with the sides of the lifting fire bar prevent lateral movement 55 of said lifting fire bar.

In some instances we may deem it advisable to connect a series of these reversible lifting fire bars and for this purpose we have provided an angular opening 26 which is 60 adapted for the reception of an angular bar, which extends across the grate and thus connects a series of the reversible lifting fire bars.

Having thus described our invention, what

we claim as new and desire to secure by 65 Letters Patent, is:—

1. In a device of the character described, a hollow lifting fire bar having a plurality of seats, and a plurality of supports for said seats, one of said supports serving as a guide 70 for the bar in its movements when the other support serves as the pivot for the bar.

2. In a device of the character described, a hollow lifting fire bar having a plurality of seats and having a curved slot, and a 75 plurality of supports disposed in said slot and adapted to form one the pivot and the other the guide for the bar in its rocking movement depending upon the direction in which the bar is rocked.

3. In a device of the character described, a hollow lifting fire bar having a plurality of seats and having a curved slot, and a plurality of supports disposed in said slot and adapted to form one the pivot and the other the guide for the bar in its rocking movement, depending upon the direction in which the bar is rocked, said supports being always in engagement with the walls of said slot.

4. In a device of the character described, a hollow lifting fire bar having a plurality of seats and having a curved slot, and a plurality of supports disposed in said slot and adapted to form one the pivot and the other the guide for the bar in its rocking movement, depending upon the direction in which the bar is rocked, and fixed means at the upper edges of the lifting bar for preventing escape of the fuel therefrom.

5. A hollow lifting fire bar for grates having a perforated upper face, perforated front and rear faces curved toward each other and side faces having a guide slot having upwardly diverging curved portions therein, the upper ends of which slot terminate in seats for the supports upon which the bar may be rocked and whereby one of the said supports serves as a guide to cause the bar to move in the same vertical plane when the bar is rocked on the other support.

6. A hollow lifting fire bar for grates having a perforated upper face and perforated front and rear faces curved toward each other, side faces having a guide slot having upwardly diverging curved portions therein, the upper ends of which terminate in seats for the supports on which the bar may be rocked, whereby one or the other of said supports serves as a guide to cause the bar to move in the same vertical plane when the bar is rocked on the other support, and means on the bar for attachment with its actuating means.

7. A hollow lifting fire bar for grates formed of separable upper and lower sections and having a perforated upper face, perforated side wings, and a guide slot having

upwardly diverging curved portions, the upper ends of which form the seats for the supports of the bar.

8. A hollow lifting fire bar composed of 5 an upper section having a perforated upper face and perforated depending wings and a lower separable section having a guide slot having upwardly diverging curved portions forming seats for the supports of the bar.

10. A hollow lifting fire bar formed of 15 upper and lower sections, means for securing the same together, depending wings on said upper section, front and rear walls on said lower section, side walls on said lower section, forming with said wings curved slots, the side walls of the upper section being provided with recesses coincident with the upper ends of said slots and forming seats adapted to receive supports upon either of 20 which the bar may be rocked.

10. A hollow lifting fire bar for grates having a perforated upper face and per-

forated front and rear faces and transversely extending shoulders on said upper face at opposite edges thereof, said bar being formed 25 with a guide slot having upwardly diverging curved portions for the reception and guidance of supports for the bar.

11. A hollow lifting fire bar for grates having a perforated upper fuel supporting 30 face, perforated flat side wings, perforated front and rear faces converging toward each other from the upper portion to the lower.

12. A hollow lifting fire bar for grates having a perforated upper face, perforated 35 side wings, perforated front and rear faces, and a guide slot having upwardly diverging curved portions in each side wing thereof.
